UNITED STATES PATENT OFFICE.

WILLIAM W. LEACH, OF MANSFIELD, OHIO, ASSIGNOR OF ONE-HALF TO ALBERT I. DAVEY, OF MANSFIELD, OHIO.

POLISHER.

1,253,697.

Specification of Letters Patent. Patented Jan. 15, 1918.

Application filed March 29, 1917. Serial No. 158,471.

To all whom it may concern:

Be it known that I, WILLIAM W. LEACH, a citizen of the United States of America, residing at Mansfield, in the county of Rich-
5 land and State of Ohio, have invented cer-
tain new and useful Improvements in Pol-
ishers, of which the following is a specifica-
tion.

This invention relates to an improve-
10 ment in polishers, primarily for use in
cleaning and polishing the periphery of
rollers used for rolling sheet steel or the
like in rolling mills and catch the refuse
and broken parts of the carborundum
15 blocks.

The general type of polisher used for the
purpose noted comprises a block or holder
in which is removably clamped carborun-
dum blocks or sections, the device as an en-
20 tirety being brought into contact with the
rolls for the purpose of cleaning and pol-
ishing the surfaces thereof.

The device is movable longitudinally of
the rolls and the pressure of the carborun-
25 dum blocks against the surface of the rolls
is regulated at the will of the operator. In
the use of this type of polisher, the material
cleaned from the rolls, and frequently parts
30 of the carborundum blocks shipped or
broken therefrom under unusual pressure
by the operator, will adhere to or pass be-
tween the rolls, and result in a pitting or
marring of the roll surface, with a result-
ant defect in the rolled sheets.

35 The main object of the present invention
is the provision of means carried by and
forming part of the polisher, which means
serves to remove from the surfaces of the
rolls and catch the guidings and broken
40 parts of the block immediately following
the action of the carborundum blocks there-
on, any and all material which would other-
wise have a deleterious effect upon the roll
surface.

45 A further object of the invention is the
mounting of the combined cleaners or
scrapers and refuse catchers of the present
invention in such relation to, and under
such connection with the polishing block
50 proper, that practically universal movement
of the combined cleaner and refuse catcher
as a whole, with relation to the polishing
block, is permitted, whereby a completely

effective and automatic adjustment of the
combined cleaning and refuse catching de- 55
vice is had under all circumstances, and in
any and all positions of the polishing block.

A further object of the invention resides
in the independent mounting of the com- 60
bined cleaning and refuse catching members
proper with respect to their supporting
plate, and the independent tensioning of
such members, to insure their individual
compensation for any irregularities.

The invention, in the preferred form of 65
details, will be described in the following
specification, reference being had therein to
the accompanying drawings, in which:—

Figure 1 is a view in elevation, partly in
section, illustrating the application of the 70
improved polisher.

Fig. 2 is a top plan view, partly in sec-
tion of the combined cleaner and refuse
catcher attachment.

Fig. 3 is a side elevation of the same. 75

Fig. 4 is an end elevation of the same,
parts being shown in their relation to the
clamping block of the polisher, and various
positions of the attachment being shown in
dotted lines. 80

Fig. 5 is an enlarged section on line 5—5
of Fig. 4.

Fig. 6 is a broken perspective of the
clamping rod for supporting the attach-
ment. 85

The general type of polisher with which
the invention is to be associated, is here con-
ventionally shown as comprising a main 90
block 1, of appropriate dimensions, formed
in the relatively upper surface thereof with
recesses 2, shaped to accurately receive car-
borundum or other polishing elements 3.
The recesses are so shaped, and the polishing
elements are so formed that when held in
said recesses the said elements present their 95
outer or operating surfaces 4, in positions
to engage the peripheral surfaces 5 of the
rolls 6. The polishing elements 3 are held
in place by a clamping block or plate 7,
which overlies and bears upon the polishing 100
elements above the main block, the clamp
plate being held in clamped relation through
clamping rods 8, which extend through the
main block and are formed with wedge pro-
jections 9, to seat in corresponding openings 105
10 in the clamp plate.

The clamping rods are secured at their lower ends below the main block by nuts 11, whereby proper clamping action may be had to secure the polishing elements in place. 5 The main block is provided with a handle 12, whereby the polisher may be initially positioned and pressure of the polishing elements on the surfaces of the rolls and movement of the polisher longitudinally of 10 the rolls is had through a hand-controlled lever 13, of right-angled formation, supported upon a guide bar 14, secured at its respective ends to the roll housing 15. The lever has a terminal foot 16 to underlie the 15 main block. As the guide bar 14 extends longitudinally of the rolls, it is apparent that through this lever the necessary pressure of the polishing elements on the surfaces of the rolls, and the adjustment of 20 the polisher as a whole longitudinally of the rolls may be readily had at the will of the operator.

In the use of a polisher such as described, and which it is understood is of usual commercial form, no provision is made, beyond that of gravitational influence for taking care of the refuse cleaned from the rolls by the polishing elements. It frequently happens that as a result of undue pressure by the operator, portions of the polishing elements will be chipped therefrom, and this, if permitted to remain in contact with or pass between the rolls will necessarily result in marring or pitting the roll surface. 30

35 To obviate this difficulty, and to insure that the surface of the rolls will be thoroughly and effectively cleaned of any and all material thereon which would otherwise have a deleterious effect upon the roll surface, there is provided an improved cleaner and refuse catcher, forming the subject matter of this invention.

This combined cleaner and refuse catcher comprises a supporting plate 17, mounted 45 above the clamp plate, and so connected as to have practically universal movement with respect thereto. To provide for this connection of the supporting plate, the clamping rods 8 are extended above the clamp plate, 50 such extensions 18, passing through openings 19 in the supporting plate, which openings are preferably elongated transversely of the supporting plate and of greater width than the diameter of the clamping rods. 55 The openings 19 are therefore in both the major and minor dimensions materially greater than the diameter of the clamping rods, to permit free play of the supporting plate with respect to the clamp plate. End- 60 wise separation of the supporting plate from the clamping rods is prevented by terminal nuts 20 upon the upper ends of said rods, above the supporting plate. The respective side edges of the supporting plate are 65 formed to present one member of a hinge

connection, the coöperating member being formed on the combined cleaners and refuse catchers 21—21.

The combined cleaners and refuse catchers here shown are crescent shaped members 70 with side walls 22, merging at the respective ends into coincidence with the similar edges of the bottom wall, whereby to present a comparatively sharp scraping or cleaning edge 23 at the free end of each cleaner and refuse catcher and provide a depression or groove 23' forming a pocket. The edges are adapted to engage the surface of the rolls and refuse catcher and act to scrape or clean the material therefrom. The combined 75 cleaners and refuse catchers proper open outwardly, that is, present their open sides next the surfaces of the roll so that when said cleaners are in operative positions with respect to the rolls, as shown in Fig. 1, they 80 present in effect receptacles or pockets in which a very considerable portion of the refuse scraped from the rolls or broken parts from the carborundum blocks will be caught and retained in the upper pocket and prevented from working between the rolls by 85 the edge of the lower pocket.

The combined cleaners and refuse catchers proper are held against movement in the relatively outward direction, by lips 24, projecting from the inner surface of the cleaners, and engaging at their inner ends beneath the head 25 of a rivet 26, secured to and projecting outwardly from the central portion of the supporting plate 17. The 100 combined cleaners and refuse catchers are further held at this limit of outward movement, while at the same time comparatively free to yield inwardly, by tensioning means, comprising spring-arms 27, preferably forming the terminals of a coil 28, encircling one of the clamping rods 8, which is extended upwardly for this purpose. The extension of the clamping rod 8 is sufficient to position the tensioning member above the rivet head, 110 the coil of said member being held on the rod between holding means 29, as cotter pins or the like. The spring arms 27, which are of considerable length, have lateral terminals 30, engaging elongated openings 31, in the inner walls or bottoms of the combined cleaners and refuse catchers. As the polishing device, with the attached combined cleaners and refuse catchers is moved into coöperation with the rolls, the surfaces of 115 said rolls force the combined cleaners and refuse catchers proper inwardly against the tension of the spring arms 27, until when the polishing elements are in proper position with relation to the surfaces of the rolls, the scraping edges of the combined cleaners and refuse catchers will be held under spring pressure against the roll surfaces above the polishing elements in the direction of rotation of the rolls. In the normal positions 120 125 130

of the parts, the supporting plate 17 is, of course, held above and in spaced relation to the clamp plate 7, and from the universal connection of the supporting plate with the 5 clamp plate, it is apparent that the supporting plate may move vertically, horizontally in angular relation to the supporting plate 17, or tilt laterally to a degree limited only by the space between said supporting plate 10 and clamp plate and slots formed in the supporting plate. This universal movement of the supporting plate is important, in that it permits a ready accommodation, and instant automatic adjustment of the cleaners, 15 to compensate for any irregularities of the rolls or polishing elements. As a result of this, combined with the independent spring pressed action of the combined cleaners and refuse catchers proper, it is apparent that 20 each combined cleaner and refuse catcher will be automatically maintained in contact with its particular roll surface, under any and all conditions of action, and hence all refuse material will be scraped or cleaned 25 from the surfaces of the rolls or caught in the groove or depression of the combined cleaner and refuse catcher.

The combined cleaner and refuse catcher construction, which forms the subject matter 30 of the present invention, is here shown as structurally adapted for coöperation with the particular type of polisher indicated. It is, of course, apparent that any and all specific changes necessary to adapt the general type 35 of combined cleaner and refuse catcher here shown and described to any other particular type of polisher proper, is necessarily an incident of the present invention, the sole requirement in this particular being that 40 the supporting plate of the combined cleaner and refuse catcher structure be so mounted, with relation to the polisher proper, as to have practically a universal play thereon, in order that a perfect compensation for irregularities of the rolls, their vibration in operation, and irregularities of the polishing elements 45 may be had.

What is claimed as new, is:—

1. A polisher for use with a plurality of 50 rolls, including a combined double scraper and refuse catcher and a universal connection between such scraper and catcher and such polisher.

2. A polisher for use with a plurality of 55 rolls, including a combined double scraper and refuse catcher carried by the polisher and means for supporting the scraper and catcher on the polisher to permit a free movement of such scraper and polisher to- 60 ward and from the polisher.

3. A polisher for use with a plurality of 65 rolls, including a combined double scraper and refuse catcher, a support on the polisher, and means carried by the scraper and catcher to engage the support to permit a

free tilting movement of such scraper and catcher with respect to the polisher.

4. A polisher for use with a plurality of 70 rolls, including a supporting plate mounted for universal movement with respect to the polisher, and a combined double scraper and refuse catcher having hinged connection with said plate.

5. A polisher for use with a plurality of 75 rolls, comprising polishing means, a supporting plate having a universal connection with the polisher, a combined scraper and refuse-catcher for coöperation with each roll, each scraper having hinged connection with the plate, and a spring mounted on 80 the plate and engaging both scrapers to exert pressure thereon toward the rolls.

6. A polisher for use with a plurality of 85 rolls, including a supporting plate having universal connection therewith, and a plurality of spring-pressed combined scrapers and refuse catchers movably connected with the plate.

7. A combined scraping and refuse catching attachment for roll polishers, comprising 90 a supporting plate, combined cleaners and refuse catchers having hinged connection therewith, means carried by the plate to exert an outward pressure on the combined cleaners and refuse catchers, and co- 95 operating means carried by the plate and combined cleaners and refuse catchers to limit the outward movements of the latter.

8. A combined scraping and refuse catching attachment for roll polishers, comprising 100 a supporting plate, combined cleaners and refuse catchers having hinged connection therewith, spring arms carried by the plate and engaging the combined cleaners and refuse catchers, and limiting stops carried by 105 said combined cleaners and refuse catchers and plate to limit movement of said combined cleaners and refuse catchers.

9. A combined scraping and refuse catching attachment for roll polishers, comprising 110 a supporting plate, crescent shaped combined cleaners and refuse catchers of hollow formation having hinged connection with the plate, spring means for exerting an outward pressure on said combined cleaners and refuse catchers, and coöperating 115 stops carried by the plate and combined cleaners and refuse catchers.

10. A roll polisher comprising a main block formed with recesses to receive polishing elements, a clamp plate to overlie said elements, clamping rods engaging the block and clamp plate to hold the latter in clamping coöperation, a combined scraper and refuse catcher supporting plate loosely 120 mounted upon said rods above the clamp plate, and combined cleaners and refuse catchers having connection with the supporting plate.

11. The combination in a roll polisher, of 130

- means to polish both rolls simultaneously, means for catching the refuse from one roller and at the same time scraping said roller, means for scraping the other roller 5 and preventing foreign substances from working between both of said rollers; said scraping means being mounted for universal movement to accommodate itself to the irregularity of both rolls.
- 10 12. In a roll polishing device, means to polish a plurality of rolls simultaneously, separate means for simultaneously scraping both rolls which is mounted upon the polishing means to permit of universal movement 15 with respect to the rolls.
13. In a roll polishing device, means to polish a plurality of rolls simultaneously, separate means for simultaneously scraping both rolls which is mounted upon the polishing means to permit of universal movement 20
- with respect to the rolls, and a single means of yieldingly maintaining said scraping means in contact with both rolls.
14. In a polishing device, means for polishing a plurality of rolls simultaneously, 25 scraping means for the rolls attached to the polishing means for pivotal and universal movement with respect to the rolls.
15. In a polishing device, means for polishing a plurality of rolls simultaneously, 30 scraping means for the rolls attached to the polishing means for pivotal and universal movement with respect to the rolls, and means to slide the polishing and attached scraping means in a horizontal direction with respect to the rolls and to force said polishing means in contact with the rolls.

In testimony whereof I affix my signature.
WILLIAM W. LEACH.
